UNITED STATES PATENT OFFICE

130,838

DESIGN FOR A HUMIDIFIER

Lurelle Guild, Darien, Conn., assignor to Electro-lux Corporation, New York, N. Y., a corporation of Delaware

Application November 7, 1941, Serial No. 104,085

Term of patent 14 years

To all whom it may concern:

Be it known that I, Lurelle Guild, a citizen of the United States of America, residing at Darien, in the county of Fairfield and State of Connecticut, have invented a new, original, and ornamental Design for a Humidifier, of which the following is a specification, reference being had to the accompanying drawings, forming a part thereof and of which:

Fig. 1 is a side elevational view of a humidifier embodying my new design;

Fig. 2 is a top plan view of the humidifier illustrated in Fig. 1;

Fig. 3 is an end elevational view of the humidifier illustrated in Figs. 1 and 2; and

Fig. 4 is a perspective view of the humidifier illustrated in the previous figures.

I claim:

The ornamental design for a humidifier, as shown.

LURELLE GUILD.
